ALBERT ASLESON, OF REDWOOD FALLS, MINNESOTA.

DETACHABLE MAINSPRING FOR CLOCKS.

1,173,081.

Specification of Letters Patent. Patented Feb. 22, 1916.

Application filed May 12, 1915. Serial No. 27,605.

To all whom it may concern:

Be it known that I, ALBERT ASLESON, a citizen of the United States, and a resident of Redwood Falls, in the county of Redwood and State of Minnesota, have invented 5 a new and Improved Detachable Mainspring for Clocks, of which the following is a full, clear, and exact description.

This invention relates to clocks and particularly to the springs thereof and means 10 for holding the same in place, and has for an object the provision of an improved arrangement whereby the main spring of a clock may be removed without disturbing 15 the remaining part of the works of the clock.

Another object of the invention is to provide removable supports for the shaft of the main spring of a clock whereby the shaft 20 and the main spring may be bodily removed without molesting the adjustment or position of the other parts of the clock.

In the accompanying drawings; Figure 1 is a fragmentary top plan view of part of 25 a clock showing the main spring and associated parts and removable means embodying the invention for holding the spring in place; Fig. 2 is a section through Fig. 3 partly on line 2—2; Fig. 3 is a sectional view 30 through Fig. 1 on line 3—3; Fig. 4 is a detail fragmentary sectional view through Fig. 1 on line 4—4; Fig. 5 is a fragmentary top plan view of one of the plates forming part of the frame of the clock; Fig. 6 is an 35 inverted detail perspective view of one of the retaining plates adapted to fit in the notch shown in Fig. 5; Fig. 7 is an inverted detail perspective view of the retaining hook washer shown in Fig. 4.

40 Referring to the accompanying drawings by numerals, 1 indicates the top plate of a clock of any suitable construction and 2 the bottom plate, the same forming part of the frame which is common to all clocks, said 45 frame being designed to hold the various works in proper position. The particular construction and arrangement of plates 1 and 2 form no part of the present invention except the notch 3 shown in Fig. 5 and the 50 notch 4 shown in dotted lines in Fig. 1, whereby the retaining plate 5 may be removed or applied at will and also the hook washer 6 may be likewise applied and removed as well. The spring 7 is of the usual 55 type and has one end secured in any suitable manner to a shaft 8 while the opposite end

is provided with a loop fitting over the standard 9 in the usual manner. Shaft 8 is journaled at the lower end in plate 2, while the upper end is journaled in any suitable way to plate 5. Plate 5 is provided with a tubular section 10 fitting into the notch 3' while the overhanging flange 11 fits on the surface of the plate 1, as shown in Fig. 3. Plate 5 is provided with a body 12 adapted to fit against the outer surface of plate 1 while the tongue or thickened portion 13 fits in the notch 3. A plurality of retaining screws 14 are provided which extend through suitable apertures in the body 12 and into plate 1 so as to hold plate 5 against movement.

In forming the invention the aim is to provide means which may be readily adjusted or operated so that the main spring of a 75 clock may be quickly and easily applied and removed without molesting the remaining part of the works of the clock and without taking the plates 1 and 2 apart. By providing plate 5 and screws 14 means are provided which when released may be moved so as to swing the shaft 8 slightly to one side and thereby unhook or disconnect the flange 11 from plate 1, which will allow the shaft to be raised until the lower end is disconnected from plate 2. In order to hold the spring 7 properly in place a retaining 80 guard ring 15 is provided which will prevent the expansion of the spring beyond a certain extent. After the shaft 8 has been 90 removed as set forth the spring 7 and wheel 16 with associated parts may be bodily removed with the exception of the loop fitted over the post or standard 9. In order to remove this loop standard 9 is connected in 95 the usual manner with the bottom plate 2, the connection being somewhat loose when nut 17 is somewhat unscrewed.

The upper end of the standard 9 extends 100 through the plate 1 and is held in position by member 6 which is provided with a hook 18 and a filling block 19, filling block 19 filling the aperture 4 while hook 18 prevents the hooked washer 6 from moving, a suitable nut being mounted on the standard and 105 pressing against member 6. When the nut 20 is appreciably unscrewed or removed the hook member 6 may be moved out of place so as to allow standard 9 to swing away from plate 1 a sufficient distance for permitting the loop 7' on spring 7 to slip 110 off of the standard, thus entirely freeing the

spring 7 and associated parts from the frame of the clock and the various works therein. After the spring has been removed the same may be repaired or a new one substituted 5 and replaced quickly without molesting in the least any of the remaining parts of the clock. This arrangement of parts prevents the necessity of readjusting the balance wheel, hair spring and other parts when a 10 new main spring is substituted for an old one. It is evident that a plate 5 could be arranged at both ends of the shaft 8, if desired, without departing from the spirit of the invention, though only one plate is 15 shown as ordinarily this is sufficient.

What I claim is:—

In a device of the character described, the combination with a clock provided with a frame, a standard, and works mounted in said 20 frame, said frame being formed of a pair of

plates, one of said plates being provided with a notch adapted to receive one end of said standard, said standard being adapted to be connected with one end of the spring of said clock, a hook member having a pair of depending hook portions, said hook member being arranged on said standard with one hook portion fitting into said notch and the other hook portion overlapping part of said frame, and a clamping member engaging said standard and pressing against said hook member for preventing the same from becoming disengaged from said frame.

In testimony whereof I have signed my name to this specification in the presence of 35 two subscribing witnesses.

ALBERT ASLESON.
